The ornamental design for a lid, as shown and described.

DESCRIPTION

FIG. 1 is a top and front perspective view of a lid, showing our new design;

FIG. 2 is a top and rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken seam line going around the body of the lid forms no part of the claimed design. The other broken lines illustrate environmental structure and parts of the article that form no part of the claimed design.
